THYROIDECTOMY RETRCTOR

Howard Mahorner, New Orleans, La., assignor to
A. S. Aloe Company, St. Louis, Mo., a corpora-
tion of Missouri

Application July 15, 1949, Serial No. 104,864

6 Claims. (Cl. 128—20)

1

This invention relates in general to surgical instruments and more particularly to certain new and useful improvements in thyroidectomy retractors.

It is the primary object of the present invention to provide a thyroidectomy retractor which may be adjusted so that a firm and secure grip will be effected upon the skin flaps and subcutaneous tissue in the surgical field without danger of slippage.

It is a further object of the present invention to provide a thyroidectomy retractor which is so designed as to present a wide field of operation and to avoid interference in any way.

It is an additional object of the present invention to provide a thyroidectomy retractor having curved portions adapted to rest athwart the patient's neck with the side portions removed from the field of operation by disposition laterally adjacent the patient's neck.

With the above and other objects in view, my invention resides in the novel features of form, construction, arrangement, and combination of parts presently described and pointed out in the claims.

In the accompanying drawing—

Figure 1 is a perspective view of a thyroidectomy retractor constructed in accordance with and embodying the present invention, as shown in relative operative position;

Figure 2 is a transverse sectional view taken along line 2—2 of Figure 1; and

Figure 3 is a transverse sectional view taken along line 3—3 of Figure 2.

Referring now in more detail and by reference characters to the accompanying drawing, which illustrates a preferred embodiment of my invention, A designates a thyroidectomy retractor comprising a pair of spaced, parallel side bars 1, 1', formed preferably of straight stainless steel rod and being provided on one of their ends with inwardly extending cone-like fittings 2, 2', respectively. Threaded at its ends within the fittings 2, 2', is a transversely extending sustaining rod 3 centrally provided with a forwardly and outwardly extending, symmetrical curved portion 4 which is inclined at an angle of approximately 44° to the plane of the bars 1, 1'. Disposed centrally upon, and suitably secured to, the sustaining rod 3 is a blade 5 having a plurality of downwardly and outwardly curved prongs 6 in claw-like formation.

Slidably disposed on each of the bars 1, 1', are sleeve elements 7, 7', respectively, each being integrally provided with transverse, cylindrical portions 8, 8', respectively, the outer ends of which are drilled and tapped for receiving knurled thumbscrews 9, 9', respectively, adapted to engage the bars 1, 1', and thereby lock the sleeves 7, 7', in any selected position of adjustment. The cylindrical portions 8, 8', extend laterally inwardly with respect to the sleeves 7, 7', and are suitably secured to the ends of a

2

sustaining rod 10 extending transversely therebetween. The sustaining rod 10 is centrally bent in the provision of a symmetrically curved portion 11 extending forwardly and upwardly in substantially parallel relation to the curved portion 4 of the sustaining rod 3. Welded or otherwise suitably secured centrally upon the curved portion 11 of the sustaining rod 10 is a blade member 12 having a plurality of prongs 13 downwardly and outwardly extending in opposite direction to that of the prongs 6 of the blade 5. It will thus be seen that the thyroidectomy retractor A forms a unique polygonal or substantially four-sided device which, in effect, forms a closed frame around the operative field and extends laterally outwardly therefrom so that the mechanical adjustment elements and other parts which might interfere with the surgeon's manipulations are fully removed from the operative zone.

20 In usage, after an incision has been made in the performance of an operation for the removal of the thyroid gland or a portion thereof, the retractor A is positioned upon the patient's neck with the sustaining rods 3, 10, disposed horizontally thereacross (see Figure 1) and the prongs 6, 13, of the blades 5, 12, respectively, are placed beneath the skin flaps and the subcutaneous tissue. The sustaining rods 3, 10, are then separated

25 until the desired width of the field of operation is reached. Whereupon, the knurled thumbscrews 9, 9', are tightened to provide a two-point contact for maintaining the sustaining rod 10 firmly in the selected position, being thereby prevented from slipping during the operation. This adjustability feature permits the retractor A to be equally useful in presenting a clear space for operating whether a small or a relatively large field of operation is desired. It will thus be noted that 30 in actual use the bars 1, 1', and the portions of the sustaining rods 3, 10, adjacent thereto, will be disposed in lateral relation to the patient's neck and thus be totally removed from the immediate field of operation.

35 It should be understood that changes and modifications in the form, construction, arrangement, and combination of the several parts of the thyroidectomy retractor may be made and substituted for those herein shown and described 40 without departing from the nature and principle of my invention.

Having thus described my invention what I claim and desire to secure by Letters Patent is:

45 1. A thyroidectomy retractor comprising a pair of spaced bars, a first rod secured rigidly at its ends to the bars and extending transversely therebetween for presentation athwart a patient's neck, said first rod having a central curved portion 50 extending forwardly and outwardly at an angle to the plane of the bars for disposing said bars in downward relation to the field of operation to prevent interference with the operative procedure, a blade disposed centrally upon said curved por-

tion of said first rod, said blade having a plurality of prongs extending downwardly toward the plane of the bars and projecting in one direction, a second rod extending transversely between the bars in parallel relation to the first rod and having a centrally curved portion, a blade element disposed centrally upon the curved portion of said second rod and having downwardly extending prongs projecting in opposite direction to the prongs of the blade on said first rod, slide members mounted on said bars and connected to said second rod whereby the distance between the prongs on each rod may be optionally regulated, and means connected to said slide members for securing the second rod in any selected position upon the bars.

2. A thyroidectomy retractor comprising a pair of spaced bars, a first rod secured rigidly at its ends to the bars and extending transversely therebetween for presentation athwart a patient's neck, said first rod having a central curved portion extending forwardly and outwardly at an angle to the plane of the bars for disposing said bars in downward relation to the field of operation to prevent interference with the operative procedure, a blade disposed centrally upon said curved portion of the first rod, said blade having a plurality of prongs extending downwardly toward the plane of the bars and projecting in one direction, a second rod extending transversely between the bars in parallel relation to the first rod and having a centrally curved portion in parallel relation to the curved portion of the first rod, a blade element disposed centrally upon the curved portion of said second rod and having downwardly extending prongs projecting in opposite direction to the prongs of the blade on said first rod, slide members mounted on said bars and connected to said second rod whereby the distance between the prongs on each rod may be optionally regulated, and means connected to said slide members for securing the second rod in any selected position upon the bars.

3. A thyroidectomy retractor comprising a pair of spaced bars, a first rod secured rigidly at its ends to the bars and extending transversely therebetween for presentation athwart a patient's neck, said first rod having a central curved portion extending forwardly and outwardly at an angle to the plane of the bars for disposing said bars in downward relation to the field of operation to prevent interference with the operative procedure, a blade disposed centrally upon said curved portion of said first rod, said blade having a plurality of prongs extending downwardly toward the plane of the bars and projecting in one direction, sleeve elements disposed upon said bars for sliding movement therealong, adjusting screws engaged in said sleeves for securing same in selected position upon said bars, said sleeve elements being provided with inwardly extending cylindrical portions, and a second rod disposed in parallel relation to the first rod having its ends received within the cylindrical portions of the sleeve elements, whereby the said second rod may be disposed in selected relation to the first rod.

4. A thyroidectomy retractor comprising a pair of spaced bars, a first rod secured rigidly at its ends to the bars and extending transversely therebetween for presentation athwart a patient's neck, said first rod having its ends disposed in the same plane as said bars and being axially normal to said bars, said first rod further having a central curved portion extending forwardly and outwardly at an angle to the plane of the

bars for disposing said bars in downward relation to the field of operation to prevent interference with the operative procedure, a blade disposed centrally upon said curved portion of said first rod, said blade having a plurality of prongs, sleeve elements disposed upon said bars for sliding movement therealong, adjusting screws engaged in said sleeves for securing same in selected position upon said bars, said sleeve elements being provided with inwardly extending cylindrical portions, and a second rod disposed in parallel relation to the first rod having its ends received within the cylindrical portions of the sleeve elements, whereby the said second rod may be disposed in selected relation to the first rod.

5. A thyroidectomy retractor comprising a pair of spaced bars, a first rod secured at its ends to the bars and extending transversely therebetween for presentation athwart a patient's neck, said first rod having a curved portion extending upwardly with reference to the plane of the bars and at an angle thereto for disposing said bars downwardly from the field of operation and laterally spaced from the patient's neck, a blade element disposed on the curved portion of said first rod and being provided with tissue-engageable members extending in one direction, a second rod extending transversely between the bars, a blade element disposed on said second rod and being provided with tissue-engageable members extending in a different direction than that of the tissue-engageable members on the blade on said first rod, and slide members mounted on the bars for movement therealong and connected to the ends of the second rod whereby the distance between the tissue-engageable members on each rod may be optionally regulated.

6. A thyroidectomy retractor comprising a pair of spaced bars, a first rod secured at its ends to the bars and extending transversely therebetween for presentation athwart a patient's neck, said first rod having a curved portion extending upwardly with reference to the plane of the bars and at an angle thereto for disposing said bars downwardly from the field of operation and laterally spaced from the patient's neck, a blade element disposed on the curved portion of said first rod and being provided with tissue-engageable members extending in one direction, a second rod extending transversely between the bars having a curved portion, said curved portion of said second rod extending forwardly and outwardly at an angle to the plane of the bars, a blade element disposed on said second rod and being provided with tissue-engageable members extending in a different direction than that of the tissue-engageable members on the blade on said first rod, and slide members mounted on the bars for movement therealong and connected to the ends of the second rod whereby the distance between the tissue-engageable members on each rod may be optionally regulated.

HOWARD MAHORNER.
